UNITED STATES PATENT OFFICE.

AMEDEE DION AND BRUNO DION, OF STE. THERESE DE BLAINVILLE, QUEBEC, CANADA.

BAND-CUTTER AND FEEDER.

1,377,323.

Specification of Letters Patent. Patented May 10, 1921.

Application filed August 21, 1920. Serial No. 405,066.

To all whom it may concern:

Be it known that we, AMEDEE DION AND BRUNO DION, British subjects, farmers, residing at Ste. Therese de Blainville, in the Province of Quebec, in the Dominion of Canada, have invented certain new and useful Improvements in Band-Cutters and Feeders; and we do hereby declare that the following is a full, clear, and exact description of the same.

The present invention relates to band cutters and feeders for threshing machines and is an improvement on United States Patent No. 1,345,588, dated July 6th, 1920, and its main object is to provide an improved mechanism for feeding grain evenly to the thresher; for cutting the bands; and for spreading the grain before it reaches the cylinder.

The invention will be better understood with the aid of the accompanying drawings which form part of the application and in which:—

Figure 1 is a longitudinal side elevation of the machine, from one side thereof.

Fig. 2 is a longitudinal side elevation of the machine, one of the sides having been removed.

Fig. 3 is an end view of the machine, the casing being broken away.

Fig. 4 is a longitudinal side elevation of the machine from the other side.

Fig. 5 is an enlarged perspective detail view of the pawl operating mechanism controlled by the drum support.

Fig. 6 is a detail perspective view of the retarding spiral members and its supporting means.

Like numerals of reference indicate corresponding parts in each figure.

In the drawings, 1 indicates a feeder frame, and 2 are the side plates of the frame which are connected by suitable cross bars so as to form an open frame. A pulley 3 is mounted at one end of the multiple crank-shaft 4 which is suitably journaled in the side plates 2 of the frame, said pulley being adapted to be connected by means of a belt (not disclosed in the drawings) to any source of power.

5 are longitudinal feeding bars provided with a plurality of depending cutting teeth 6, said feeding bars being connected intermediate of their length to the multiple crank-shaft 4, and reciprocated simultaneously thereby, said bars, being connected at their rear ends

by the pivoted links 7 mounted on the cross shaft 8 journaled in the frame. On said cross shaft 8, on the exterior side of the frame, a lever member 9 is mounted, and 10 is a connecting rod projecting diagonally and at its lower end adapted to engage a crank-lever 11 which oscillates the pivoted pan 12 mounted below frame 1.

A feeding conveyer or carrier 13 is provided in said frame 1, consisting of an endless belt 14 and actuated by the sprockets 15 and chain 16, two of said sprockets 15 being mounted on the shaft 17. 18 is a gear mounted on the outer side of said frame 1, 19 on shaft 19 journaled in suitable bearings in said frame 1, and operated by the chain 20 co-acting with the gear 21, mounted on the exterior of said frame, on the crank-shaft 4. Intermediate of said chain 20, is mounted a tension pulley 22 adapted to take up the slack of said chain.

In the upper end of said frame 1 is journaled a cross shaft 23, on which is mounted the gear 24, said shaft being actuated by the chain drive 24^a which co-acts with the sprocket 25 mounted on the shaft 19. A tension pulley 25^a is mounted intermediate of said chain drive 24^a.

26 are circular members or drums movably supported on the pivotal circular U-shape members 27, each being connected by a tubular portion 28 adapted to engage and be supported by said shaft 23, and 29 is a horizontal projecting arm having thereon a vertical pin 30. On said drums 26 is loosely mounted the gear 31, said gear being provided on its outer periphery with a plurality of triangular teeth or cutting blades 32, which act to sever the bands on the bundles during the passage of the latter beneath, and to co-operate with the teeth 6 in cutting the bundles before they reach the cylinder. 33 are pinions mounted on the shaft 23 engaging said gears 31 and adapted to rotate the same. The said gears 31 must be large enough in diameter so as to encircle the crank-shaft 4, and said drums are so supported on said semi-circular U-shape members, as to be oscillated or rocked to and fro by the passage beneath it of a bundle cross-wise, the rocking movement being imparted to the semi-circular U-shape members 27, tubular extension 28, arm 29, which in turn will operate the arm 34 slidably mounted on the vertical rod 35 which is pivotally connected at its lower end, on the exterior side

105
110

of the frame 1, to the stop-member 36. A spiral spring 37 is mounted on the pin 30 and on the upper end of the rod 35, so as to provide a buffer, in case the machine was 5 chocked by a too large amount of straw.

The stop-member 36 is preferably pivotally mounted at 38, and is adapted to engage the pawl 39. A gear 41 mounted on the shaft 17 co-acts with the pinion 42 10 mounted on the shaft 19.

The pawl 39 is pivotally supported by means of the carrier 45 which is rigidly mounted on the shaft 17, and 46 is a spring tension adapted to contact with said 15 carrier.

On said shaft 17 is mounted adjacent the gear 41, a sprocket gear 47 connected to the gear 48 by means of the chain 49, said gear 48 being mounted on the suspended cross 20 shaft 49^a which is suitably journaled to the slightly movable or swinging bearings 50. The said shaft 49^a projects through holes 51 provided in the sides of the frame 1. The bearings 50 are mounted on the perpendicular rods 51^a and are secured to the shaft 52, 25 mounted on the brackets 53, secured in the upper portion of said frame 1. On said shaft 49^a are rigidly mounted, at suitable intervals, the retarding spiral members 54. 30 Adjacent one of said bearings 50 is provided a stop member 55 consisting of an outwardly extending portion 56, having at right angle thereto one arm 57 to which is rigidly secured the stop-arm 58 which extends longitudinally in relation to the frame 1 and is adapted to contact with the pawl 39. At the other end of said extending portion 56 is provided a downwardly projecting portion 59 which is provided with an 35 oblong slot 60 the walls of which are adapted to engage said shaft 49^a, so that it may be carried with said shaft. If a too large amount of straw comes to pass the retarding spiral members 54, the shaft 49^a will be 40 swung slightly inwardly carrying with it and thus tipping the stop-member 55, and the stop-arm 58, so that it will contact with the pawl 39, to interrupt the rotation of 45 said shaft 17.

50 A spring 61 is secured to said outwardly extending portion 56 at one end, and at its other end to the frame 1, so as to release said stop-arm 58 from the pawl 39, while a flat spring 61^a is provided to press downwardly on said shaft 49^a.

The perpendicular rods 51^a are carried to their normal position by means of the horizontal spring held rods 62, which project through a bracket 63, secured to the 60 frame 1.

65 On the other exterior side of said frame 1, is slidably mounted on the crank-shaft 4 a disk 64 which is provided on one face thereof with a laterally projecting spiral cam adapted to engage the angularly bent

bar 65 fulcrumed at 66 in the forked end 66^a of the oblique rod 67 projecting adjacent the pawl 68 mounted in the carrier 69, which is mounted on the shaft 19, the said carrier being spring-held by means of the flat spring 70 70 75 75 80 85 90 95 100 105 110 115 120 125 130

70. On one end of said angularly bent bar 65 is mounted a roller 71 adapted to contact with the spiral-cam on the disk 64, and 72 is a spring tension or resilient means provided between said bar 65 and said rod 67 which consists of a pin 73 adapted to project through a bracket 74 secured to the frame 1 around which a spiral spring 75 is mounted. A pin 76 is mounted on the bar 65, which projects through said rod 67 and around which a spiral spring 77 is mounted. The bar 65 in its normal position does not engage the spiral cam on the disk 64, but when the speed is reduced, the centrifugal governor 78 will force said disk away from the gear 21, thereby bringing the cam on said disk into position to engage said bar 65. The rod 67 will be tilted by the said bar 65 and its face end lowered slightly, as illustrated in Fig. 4 of the drawings, in which position it will engage the pawl 68 and stop the gear 18, with the result that the conveyer 13, and the retarding spiral members 54 will be stopped.

What we claim as our invention is:—

1. In a machine of the character described, the combination of a rotatable crank-shaft; a retarder drum encircling said shaft and provided with band cutters; a cross-shaft projecting through said drum; a pinion mounted on said shaft adapted to actuate said drum; a supporting member mounted on said shaft adapted to support said drum; connections between said cross-shaft and said crank-shaft for rotating the former; a carrier for delivering bundles beneath said drum; driving connections between said carrier and said cross-shaft; a centrifugal governor carried by said crank-shaft; a mechanism controlled automatically by said governor for interrupting the driving connections of said cross-shaft; and reciprocating feeding bars mounted on said crank shaft.

2. In a machine of the character specified, the combination of a rotatable crank-shaft; a retarder drum loosely encircling said crank-shaft and provided with band cutters; a cross-shaft projecting through said drum; means on said cross-shaft to actuate said drum; means on said cross-shaft to support said drum; connections between said cross-shaft and said crank-shaft for rotating the latter from the former; a carrier for delivering bundles beneath said drum; driving connections between said carrier and said cross-shaft; a centrifugal governor carried by said crank-shaft; a mechanism controlled automatically by said governor for interrupting the driving connec-

tions of said drum; and means controlled by said drum to automatically interrupt the driving connections of said carrier; and reciprocating feeding bars mounted on said 5 crank-shaft.

3. In a machine of the character specified, the combination of a crank-shaft; a retarder drum loosely encircling said crank shaft, but not supported thereon and provided 10 with cutting means; a cross-shaft projecting through said drum; means on said cross-shaft to rotate said drum; connections between said crank-shaft and said cross-shaft for rotating the latter from the former; a carrier for delivering bundles beneath said drum; driving connections between said cross-shaft and said carrier; a centrifugal governor carried by said crank-shaft; retarding members provided adjacent 15 said carrier; a mechanism controlled automatically by said governor for interrupting the driving connection of said cross-shaft; a mechanism controlled by said drum adapted to interrupt the driving connection 20 of said carrier; and an independent mechanism controlled by said retarder members adapted to interrupt the driving connection 25 of said carrier; and reciprocating feeding bars mounted on said crank-shaft.

4. In a machine of the character specified, the combination of a crank-shaft; a retarder drum loosely encircling said shaft, but not supported thereon, provided with cutting means; connections between said 30 crank shaft and said drum for rotating the former from the latter; a carrier for delivering bundles beneath said drum; driving connections between said carrier and said drum driving means; a centrifugal governor carried by said crank-shaft; means 35 under the control of said governor for automatically interrupting the driving connection between said crank shaft and said drum; means controlled by the movement 40 for automatically interrupting the operation of the driving connection of said carrier; retarding members; and means controlled by said retarder member, for interrupting said carrier driving connection; and 45 reciprocating feeding bars mounted on said crank-shaft.

5. In a machine of the character specified, the combination of a crank shaft; a retarder drum loosely encircling said crank-shaft, but not supported thereon, and provided 50 with cutting means; connections between said crank-shaft and said drum for rotating the former from the latter; a carrier for driving bundles beneath said drum; driving connections between said carrier and said drum rotating means; a centrifugal governor carried by said crank-shaft; means 55 under the joint control of said drum and said governor for automatically interrupting both driving connections; a movable 60

cross-shaft, having mounted thereon a plurality of retarder members; and means on said cross-shaft for automatically interrupting the driving connection of said carrier; and reciprocating feeding bars mounted on 70 said crank-shaft.

6. In a machine of the character specified, the combination of a crank-shaft; a retarder drum loosely encircling said shaft, but not supported thereon, and provided with cutting 75 means; a carrier for delivering bundles beneath said drum; a mechanism driven by said crank-shaft, including a train of pawls for operating said carrier and drum; a plurality of rods for interrupting the pawl 80 train; means driven by said crank-shaft for automatically controlling the operation of one of said rods; and means carried by said drum for automatically controlling the operation of the other rod; and reciprocating 85 feeding bars mounted on said crank-shaft.

7. In a machine of the character specified, the combination of a crank-shaft; a retarder drum loosely encircling said crank shaft, but not supported thereon, and provided with 90 cutting means; a carrier for delivering bundles beneath said drum; a mechanism driven by said crank shaft, including a train of pawls for operating said carrier and drum; a plurality of rods for interrupting 95 the pawl train; means driven by said crank-shaft for automatically controlling the operation of one of said rods; means carried by said drum for automatically controlling the operation of the other rod; a movable 100 cross-shaft carrying a plurality of retarding members; and means on said shaft for interrupting the driving connections of said retarder; and reciprocating feeding bars mounted on said crank-shaft. 105

8. In a machine of the character specified, the combination of a crank shaft; a retarder drum loosely encircling said crank-shaft, but not supported thereon, provided with cutting means; a carrier for delivering bundles beneath said drum; a mechanism driven by said crank-shaft, including a train of pawls for operating said carrier and drum; a plurality of rods for interrupting the pawl 110 train; means driven by said crank-shaft for automatically controlling the operation of one of said rods; means carried by said drum for automatically controlling the operation of the other rod; a movable cross-shaft carrying a plurality of retarding spiral 115 members; means on said shaft for interrupting the driving connections of said retarder; reciprocating feeding bars mounted on said crank-shaft; said feeding bars being pivotally connected at one end to a cross-shaft; a lever mounted on said cross-shaft; an oscillating pan and connecting operating means between said oscillating pan and said lever member; and reciprocating feeding bars mounted on said crank-shaft. 120

9. In a machine of the character specified, the combination of a crank-shaft; a retarder drum loosely encircling said crank-shaft, but not supported thereon, provided with cutting means; a carrier for delivering bundles beneath drum; a mechanism driven by said crank-shaft, including a train of pawls for operating said carrier and drum; a plurality of rods for interrupting the pawl train; independent means controlled by said crank-shaft and said drum for automatically controlling the operation of said rods; and means for restoring to their normal position said rods; and reciprocating feeding bars mounted on said crank-shaft.
10. In a machine of the character specified, the combination of a crank shaft; a retarder drum loosely encircling said crank-shaft, provided with cutting means; a carrier for delivering bundles beneath said drum; a cross-shaft adjacent said drum; means on said cross-shaft to rotate said drum; means on said cross-shaft to support said drum;

connections between said crank shaft and said drum for rotating the former from the latter; a carrier for delivering bundles beneath said drum; driving connections between said carrier and said cross-shaft; a centrifugal governor carried by said crank-shaft; means under the control of said governor for automatically interrupting the driving connection between said crank-shaft and said drum; means independent of said governor provided on said drum support controlled by said drum for automatically interrupting the driving connection of said carrier; and reciprocating feeding bars mounted on said crank-shaft.

Signed at Montreal, Quebec, Canada, this 3rd day of August, 1920.
